UNITED STATES PATENT OFFICE.

PATRICK T. McLAUGHLIN AND WILLIAM ANDERSON, OF MIAMI, OKLAHOMA.

BOTTLE-EXCHANGE RECEPTACLE FOR CONTAINING MILK BOTTLES.

Application filed April 3, 1926. Serial No. 99,552.

This invention relates to a bottle exchange receptacle for containing milk bottles or the like.

An important object of the invention is to provide a device of this character adapted to contain a milk bottle either full or empty and of such structure that the removal of the contained bottle is more readily accomplished by the insertion of a second bottle 10 to thereby substantially insure the substitution of an empty bottle for a full one or a full bottle for an empty one.

A still further object of the invention is to provide a device of this character having 15 means for housing the contained bottle so as to protect the same against the attacks of flies and other inserts and to hide the same from the view of mischievous boys or tramps who otherwise might attempt to remove the 20 same.

A further object of the invention is to provide a device of this character so constructed that one bottle which is inserted to release a second bottle is itself locked in position in the casing before the second bottle reaches the released position so that the inserted bottle may not be removed.

A further object of the invention is to provide a device of this character which 30 may be very readily and cheaply constructed and which will be durable and efficient in service.

These and other objects we attain by the construction shown in the accompanying 35 drawings, wherein for the purpose of illustration is shown a preferred embodiment of our invention and wherein:—

Figure 1 is a vertical sectional view 40 through a bottle exchange receptacle constructed in accordance with our invention;

Figure 2 is a section on the line 2—2 of Figure 1;

Figure 3 is a transverse sectional view 45 through the lower end of the apparatus;

Figure 4 is an enlarged detail sectional view showing the method of limiting the movement of the retaining arms.

Referring now more particularly to the drawings, the device includes an open bottomed tube 10 having at vertically spaced points brackets 11 whereby it may be secured to a suitable support, such as the wall of a building. The upper end of the tube is preferably beveled and is provided with 55 a cover 12 hinged, as at 13, and of sufficient size to insure against entry to the upper end

of the tube of snow or sleet which would collect upon the contained bottle and render the removal thereof difficult.

Within the tube at vertically spaced points 60 are arranged retaining elements 14 in the form of upwardly converging spring fingers 15 through which a bottle may be inserted from the lower end but from which a bottle once inserted may not be removed except by 65 elevation thereof. The lower set of spring fingers 15 is arranged immediately above the bottom of the tube while the second or upper set is arranged so that the upper ends of the fingers are slightly spaced from the 70 upper end of the tube.

These spring fingers are preferably each secured at their lower ends to bands 16 which fit against the interior of the tube and are riveted to the tube, as indicated at 17. The 75 fingers themselves are preferably formed of flat spring steel. The wall is provided in its lower end with a vertically extending slot 18 which extends a short distance above the upper ends of the lower springs 15 and 80 the distance between the upper ends of the lower spring fingers and the upper ends of the upper spring fingers is such that if two bottles of the type which are to be employed with the exchange apparatus and which are 85 superimposed within the tube, the lower will have its lower end well above the upper ends of the lower fingers when the upper end of the upper bottle has just projected above the upper ends of the upper fingers so that 90 it is accessible through the top of the tube.

The upper and lower bands provide pivots for circumferentially spaced vertically extending rods 19, the upper and lower ends of which are formed with arms 20 and 21. 95 The arms 21 project through openings 22 formed in the band and have coaction with the walls of this opening such that their swinging movement in one direction is limited when the arms are substantially radially directed to the walls of the tube. Each of the arms 20 and 21 is arcuately curved so that it may swing against the walls of the tube and conform to the shaping thereof. A spring 23 associated with each rod tends to 100 rotate the rod in a direction maintaining the arm 21 against the stop shoulder 24 at one end of its slot and accordingly to maintain the arms 21 and 22 in a radial position. The arms 21 are located substantially at the 110 lower end of the tube and the arms 20 a distance above the arms 21 slightly less than

the combined height of two of the bottles which are to be employed with the device.

In the use of the device, assuming a bottle to be already in position therein and resting at its lower end upon the upper ends of the lower fingers 15, a second bottle is inserted through the open bottom of the tube and will engage with its walls against the arms 21, causing these arms to swing back 5 toward the walls of the tube and accordingly shift the arms 20 so as to permit the passage of the upper end of the upper bottle between such ends, thus freeing the upper bottle for vertical movement through the 10 upper fingers 14. This vertical movement through the upper fingers is obtained by engaging the lower bottle with a finger or fingers inserted through the slot 18 and elevating the same. The upper bottle does not 15 project above the upper ends of the fingers 14 until the lower bottle has passed above the upper ends of the lower fingers 15 with the result that the lower bottle is locked against withdrawal before the upper bottle 20 25 may be withdrawn, thereby preventing fraud and assuring against removal of one bottle without the substitution of a second bottle therefor. Attention is directed to the fact that the free ends of the lower arms 21 30 are bent so that they diverge downwardly, as at 21^a. The end portions of the downwardly diverging portions are then bent upwardly, as at 21^b. These downwardly diverging portions combine to form a cam against 35 which the bottle head may engage to cause the arms 21 to separate, while the upturned end portions thereof prevent the ends of these downturned portions from piercing the cap of a bottle which may be accidentally brought into engagement therewith.

Since the construction hereinbefore set forth is capable of a certain range of change and modification without materially departing from the spirit of the invention, we do 40 not limit ourselves to such specific structure except as hereinafter claimed.

We claim:—

1. A bottle exchange device comprising a tube having an open lower end and provided 50 at its upper end with a hinged cover, spaced retaining elements within the tube each permitting the upward passage of a bottle and preventing downward movement of the bottle after passage thereof, the space between 55 said retaining elements being slightly greater than the length of two bottles of the type to be employed therewith, means between the retaining elements preventing upward passage of a bottle arranged upon the lower retaining element unless followed by a second bottle comprising arms normally spring positioned in the path of the bottle and rigidly resisting upward movement of the bottle and means to be engaged by a second bottle inserted beneath the first bottle for swinging 60 65 70 75 80 85 90 95 100 105 110 115 120 125 130

said arms to the walls of the tube to permit passage of the first bottle and comprising other arms corresponding in number and arrangement to the first named arms and arranged at the lower end of the tube, the last 70 named arms permitting passage of the upper end of the bottle and being connected with the first named arms by vertically extending rods.

2. A bottle exchange device comprising a 75 tube having an open lower end and provided at its upper end with a hinged cover, spaced retaining elements within the tube each permitting the upward passage of a bottle and preventing downward movement of the bottle after passage thereof, the space between said retaining elements being slightly greater than the length of two bottles of the type to be employed therewith, means between the retaining elements preventing upward 80 85 90 95 100 105 110 115 120 125 130

passage of a bottle arranged upon the lower retaining element unless followed by a second bottle comprising arms normally spring positioned in the path of the bottle and rigidly resisting upward movement of the bottle and means to be engaged by a second bottle inserted beneath the first bottle for swinging said arms to the walls of the tube to permit passage of the first bottle and comprising other arms corresponding in number and arrangement to the first named arms and arranged at the lower end of the tube, the last 100 named arms permitting passage of the upper end of the bottle and being connected with the first named arms by vertically extending rods and a common support for each set of retaining elements and the associated arms.

3. A bottle exchange device comprising a tube having an open lower end and provided at its upper end with a hinged cover, spaced retaining elements within the tube each permitting the upward passage of a bottle and preventing downward movement of the bottle after passage thereof, the space between said retaining elements being slightly greater than the length of two bottles of the type to be employed therewith, means between the retaining elements preventing upward passage of a bottle arranged upon the lower retaining element unless followed by a second bottle comprising arms normally spring positioned in the path of the bottle and rigidly resisting upward movement of the bottle and means at the lower end of the tube and engaged by a second bottle inserted beneath the first bottle for swinging said arms to the walls of the tube to permit passage of the first bottle comprising other arms corresponding in number and arrangement to the first named arms and arranged at the lower end of the tube, the last named arms permitting passage of the upper end of the bottle and being connected with the first named arms by vertically extending rods, the free ends of the last named arms diverging down-

wardly to provide camming portions for engagement with the head of a bottle.

4. A bottle exchange device comprising a tube having an open lower end and provided at its upper end with a hinged cover, vertically extending rods pivotally supported from the interior walls of the tube and having at opposite ends thereof horizontally directed arms, springs normally maintaining the arms substantially radial to the axis of the tube and in the path of the passage of a bottle through the tube, the arms being spaced apart a distance greater than the length of the bottle to be accommodated, the lower arms having camming portions for engagement with the head of a bottle to thereby position the upper arms to permit passage of a contained bottle.

5. A bottle exchange device comprising a tube having an open lower end and provided at its upper end with a hinged cover,

vertically extending rods pivotally supported from the interior walls of the tube and having at opposite ends thereof horizontally directed arms, springs normally maintaining the arms substantially radial to the axis of the tube and in the path of the passage of a bottle through the tube, the arms being spaced apart a distance greater than the length of the bottle to be accommodated, the lower arms having camming portions for engagement with the head of a bottle to thereby position the upper arms to permit passage of a contained bottle and means between said arms for engaging the lower end of a contained bottle and supporting the same in vertically spaced relation to the lower arms. 25 30 35

In testimony whereof we hereunto affix our signatures.

PATRICK T. McLAUGHLIN.
